UNITED STATES PATENT OFFICE.

EDWARD JAMES OBER, OF TAYLOR, LOUISIANA, ASSIGNOR OF SEVEN-TWELFTHS TO CYRUS E. MILLER AND THREE-TWELFTHS TO EMMETT CONRAD, OF MINDEN, LOUISIANA.

PACKING FOR JOINTS.

No. 834,992.

Specification of Letters Patent.

Patented Nov. 6, 1906.

Application filed January 20, 1906. Serial No. 297,052.

To all whom it may concern:

Be it known that I, EDWARD JAMES OBER, a citizen of the United States, residing at Taylor, in the parish of Bienville and State of Louisiana, have invented certain new and useful Improvements in Packings for Joints, of which the following is a specification, reference being had therein to the accompanying drawing.

10 My invention relates to packings for joints, and particularly to packing for the glands of piston-rods, steam-pipes, and the like.

Among the essential requisites of a good packing for steam-engines is that it shall be unaffected by dry and moist heat and also that it shall possess substantially unimpaired elasticity after prolonged use. Hitherto these desirable features have not usually been found together. In the effort to obtain 20 freedom from deterioration by the action of the steam or by dry heat materials have been employed lacking in inherent and permanent elasticity, and as a result the joint is found to leak in time, while the defect is not 25 readily removed by a tightening of the parts, because the packing has lost the ability to respond under such pressure and fill the space. Particularly is this true in packings for stuffing-boxes employed with piston-rods 30 and other moving parts.

The packing forming the subject of this application combines the desirable characteristics enumerated, due to the natural qualities of the material employed and to those imparted by the treatment to which it is subjected, my invention residing in the packing *per se* and also in the novel method of producing the same, as will be hereinafter fully described and more particularly claimed.

40 To produce the packing, I take the husks of ordinary maize or Indian corn, remove the butts and coarse woody portions, and twist or braid the remainder by any suitable means into a compact rope of a size corresponding 45 to the joint to be packed. After twisting, the fibers may advantageously be further compacted by passing through suitably-formed rolls. The husk rope is then steamed until moist throughout and placed in a vat 50 containing a moderately-heated solution comprising of one gallon cylinder-oil, one-half pound tallow, four ounces graphite, and one ounce of glycerin. The rope is allowed

to remain in the solution and preferably kneaded until thoroughly saturated there- 55 with and then taken out, the excess of solution removed, and allowed to cool and dry in the open air. It is then superficially coated with dry graphite and stored until required for use.

I have found that a packing-rope so prepared will remain in the same condition for years without losing in any degree its qualities of excellence.

When it is desired to pack a joint, a length 65 of the rope is cut off sufficient to extend around the joint, placed in position, and pressed home by tightening the joint in the ordinary way. From time to time a further tightening of the joint will force the 70 packing into closer relation to the machine parts, the fibers of the packing rearranging themselves under pressure and retaining unimpaired their life and elasticity through a period of use beyond anything heretofore 75 known in this art.

While some of the ingredients forming the solution with which the husk is saturated may be omitted and yet results secured which are an advance as compared with 80 other packings, yet I find that the best result follows the use of all the materials in substantially the manner set out.

Having thus described my said invention, what I claim as new, and desire to secure by 85 Letters Patent of the United States, is—

1. A packing for joints consisting of steamed corn-husks impregnated with a lubricant.

2. A packing for joints consisting of 90 steamed corn-husks impregnated with oil.

3. A packing for joints consisting of a steamed corn-husk rope impregnated with a lubricant.

4. A packing for joints consisting of a 95 steamed corn-husk rope impregnated with oil.

5. A packing for joints consisting of a steamed corn-husk rope impregnated with oil, graphite and glycerin.

6. The method of making a packing for 100 joints, which consists in steaming corn-husks, saturating with a lubricant, and removing the surplus lubricant.

7. The method of making a packing for 105 joints, which consists in steaming corn-husks,

saturating with oil, and removing the surplus oil.

8. The method of making a packing for joints, which consists in forming a rope of 5 corn-husks, steaming, impregnating with a lubricant, and drying.

9. The method of making a packing for joints, which consists in steaming corn-husks, saturating with a heated mixture of cylinder-¹⁵ oil, graphite, tallow and glycerin, and removing the surplus liquid, and drying.

10. The method of making a packing for

joints, which consists in steaming corn-husks twisted into the form of a rope, saturating with a heated mixture of cylinder-oil, graphite, tallow and glycerin, and removing the surplus liquid, and drying.

In testimony whereof I hereunto affix my signature in presence of two witnesses.

EDWARD JAMES OBER.

Witnesses:

GEORGE WOODARD,
C. C. OBER.
